ABSTRACT: A tray into which a working hairdresser can deposit rollers and clips indiscriminately as the same are removed from the hair of a beauty parlor patron is disclosed. Above its bottom, the tray has a screen arrangement which permits clips to fall through but not rollers, and at one end of the tray, a recess in the screen arrangement provides access to the lower region of the tray for manual removal of accumulated clips. If clips are required for use on another patron, the tray is tilted toward the recess to cause the clips to slide to that end of the tray from where they may then be removed with no time wasted in separating them from the rollers. An auxiliary receptacle, preferably having the contours of the recess, is normally positioned in the tray at the recess and may be used as a depository for the clips taken from the tray.

BEAUTY PARLOR ACCESSORIES

This invention relates to beauty parlor accessories, and more particularly to trays adapted to be used by hairdressers or beauticians as depositaries for rollers and clips.

Beauticians, when in the process of removing rollers and clips from the hair of a patron whose hair has been set, usually deposit such items in a helter-skelter fashion on a convenient shelf or like surface or in a nearby receptacle. If, in the mean time, the clips are to be used in setting the hair of another patron, the jumble of both rollers and clips makes the separation of the clips difficult and time consuming and considerably reduces the beautician's working pace.

It is an important object of the present invention, therefore, to provide a novel construction of a hairdresser's tray by means of which the foregoing drawbacks and disadvantages can be avoided.

More specifically, it is an object of the present invention to provide such trays adapted to be used as depositaries for both rollers and clips but in a manner facilitating separation of the clips from the rollers and removal of the clips for further use.

Generally speaking, the objectives of the present invention are attained by the provision of a tray having a screen arranged thereacross above its bottom. The beautician, when removing clips and rollers from the hair of a patron, merely drops them indiscriminately onto the screen, the openings of which are large enough to permit the clips but not the rollers to fall through into the lower region of the tray. A recess in the screen at one end of the tray provides access to the lower tray region to enable accumulated clips to be extracted therefrom after appropriate tilting of the tray to cause the clips to slide to that end thereof where the screen is recessed. The tray preferably also includes an auxiliary receptacle into which extracted clips may be put for transfer to another station where they are to be used. In an especially advantageous construction according to the invention, two vertically spaced screens are provided in the tray, the upper one retaining the rollers, and the lower one retaining the clips. Loose hairs and other waste materials can then fall through the lower screen as well and accumulate on the tray bottom and away from the clips, preferably in a removable drawer.

The foregoing and other objects, characteristics and advantages of the present invention will be more clearly understood from the following detailed description thereof when read in conjunction with the accompanying drawings, in which:

FIG. 1 is a perspective view of a hairdresser's tray constructed in accordance with one aspect of the present invention;

FIGS. 2 and 3 are, respectively, sectional views taken along the lines 2-2 and 3-3 in FIG. 1;

FIG. 4 is a fragmentary sectional view, similar to FIG. 2 and illustrates the tilting of the tray to cause clips to slide to one end thereof preparatory to removal therefrom; and

FIG. 5 is a sectional view, similar to FIG. 2, of a tray constructed in accordance with another aspect of the present invention.

Referring now to the drawing in greater detail, there is shown in FIG. 1 a tray 10 which is preferably rectangular in outline as illustrated, although, as will be clear, it may be square or otherwise shaped. The tray may be made of any suitable material, e.g. synthetic plastics, metal and the like, and advantageously may be about 15 inches long, 9 inches wide, and 7 inches high. Two screens or grids 11 and 12 are arranged within the tray, with the latter extending across the entire expanse thereof, at respectively different elevations above the bottom of the tray. The two screens or grids may rest loosely on, or be secured to respective ledges 11a and 12a. The upper screen 11 extends across a substantial portion of the expanse of the tray and at one end, e.g. one corner, terminates short of the proximate sidewall structure of the tray, to define a recess 13 (FIGS. 2 and 4). The recess is shown to be square or rectangular in outline, but here again it will be understood that the shape of the recess may be otherwise than

as illustrated. An auxiliary receptacle 14 the contours of which preferably are mated to those of the recess, is shown as resting in the tray on the lower screen 12 within the confines of the recess. If desired, a cover (not shown) may be provided for the tray.

The openings in the upper screen 11 are so dimensioned as to prevent passage of rollers 15 therethrough while permitting passage of smaller items, i.e. the clips 16. At the same time the openings in the lower screen 12 are sufficiently large to permit hairs, dandruff particles and other waste materials to drop therethrough but not the clips 16. The space between the two screens should be sufficient to accommodate the clips, i.e. about 2½ inches high. The space in the tray 10 below the lower screen 12, advantageously about three-fourths of an inch in height, is occupied, in accordance with this embodiment of the invention, by a drawer 17 having a knob or other pull 18. Along the edge of the recess 13, the screen 11 is preferably also provided with an upstanding barrier portion 19, for example a strip of the same material of which the tray is made, the purpose of which will become clear as the description proceeds.

In the use of the tray 10, it will be understood that the beautician, having the tray nearby, upon removing the rollers and clips from the hair of a patron whose hair is being set, is able simply to drop them into the tray without taking the time or any special pains to keep them separate. This work can thus be done at maximum speed. By virtue of the dimensioning of the openings of the screen or grid 11, the rollers 15 remain on the upper screen, but the clips fall therethrough and accumulate on the lower screen 12. The rollers 15 can, of course, be picked off the upper screen 11 whenever desired. Should a supply of clips be required for another hairsetting operation, however, the beautician merely has to take the tray and cant it gently toward corner where the recess 13 is located, as indicated by the arrow A in FIG. 4, jiggling it slightly if necessary, to cause the accumulated clips 16 on the lower screen 12 to slide over toward the end of that screen underlying the recess 13. The auxiliary receptacle 14 having been previously removed, the clips can then be extracted from the tray for removal to another working location, being, if desired, placed into the auxiliary receptacle and carried therein over to the location where they will be used. The barrier 19 serves to prevent or restrain the rollers 15 from falling into the recess 13 and down onto the lower screen 12, especially when the tray is tilted.

It will be apparent, of course, that the barrier 19 may be constructed otherwise than as shown. Thus, if the recess 13 extends across the entire width of the tray, the barrier may be defined simply by an end region of the screen bent up across its entire width, in which case the auxiliary receptacle or clip box 14 may also be correspondingly enlarged. Alternatively, the barrier need not necessarily be coincident with the boundary of the recess, and if provision is made in some other way to prevent the rollers from falling into the recess, for example, by making the receptacle 14 somewhat shallower to permit it to remain in the recess and act as a restraining structure for the rollers without interfering with the shifting of the clips while the tray is being tilted, then the barrier 19 may be omitted altogether. Quite obviously, if a barrier 19 is provided, the auxiliary receptacle need not rest in the tray at all but may be supported exteriorly thereof and may even be dispensed with.

The tray 10' according to the embodiment of the invention illustrated in FIG. 5 is a somewhat simplified version of the tray 10, differing therefrom only in that the lower screen 12 and the drawer 17 are omitted. Thus, the tray 10' is provided only with a single screen or grid 11 having the recess 13 therein and, if desired, the barrier 19 associated therewith, as well as openings dimensioned to retain the rollers 15 but permit the clips 16 to fall into the lower region of the tray, and the auxiliary receptacle 14 is shown as resting on the bottom of the tray although as before, this is not indispensable. The manner of use of the tray 10' is, nevertheless, essentially the

same as that of the tray 10, and a detailed description of such use at this point is believed unnecessary.

It will be understood that the foregoing description of preferred embodiments of the present invention is for purposes of illustration only, and that the various features and relationships herein disclosed are susceptible to a number of modifications and changes none of which entails any departure from the spirit and scope of the present invention as defined in the hereto appended claims.

I claim:

1. A beauty parlor accessory adapted to serve as a depository for rollers and clips as the same are removed by a hairdresser from the hair of a beauty parlor patron, comprising a tray, a screen located within and spaced from the bottom of said tray and onto which the hairdresser can deposit both rollers and clips indiscriminately, said screen extending across a substantial portion of the expanse of said tray and presenting openings which are large enough to permit clips to pass therethrough but not rollers, said screen at one end region thereof terminating short of the proximate sidewall structure of said tray to define a recess providing access to the lower region of said tray for enabling manual removal of accumulated clips therefrom, and an auxiliary receptacle removably supported by said tray and adapted to serve as a working depository for clips upon removal of the latter from said lower region of said tray, said auxiliary receptacle having the same outer contours as said recess and normally resting in said tray within the confines of said recess.

2. A beauty parlor accessory according to claim 1, said auxiliary receptacle normally resting in said tray on the bottom thereof.

3. A beauty parlor accessory according to claim 1, further comprising an additional screen extending across and spaced from the bottom of said tray intermediate the bottom of the latter and said first-named screen, the openings in said additional screen being large enough to permit hairs, dandruff and other waste material to pass therethrough but not clips.

4. A beauty parlor accessory according to claim 3, said auxiliary receptacle normally resting in said tray on said additional screen.

5. A beauty parlor accessory according to claim 3, further comprising a removable drawer arranged below said additional screen to facilitate removal of accumulated waste materials.

6. A beauty parlor accessory according to claim 1, further comprising a barrier interposed between the main portion of

said screen and said recess to restrain rollers on said screen from entering said recess and falling into the lower region of said tray.

7. A beauty parlor accessory according to claim 6, said barrier being disposed in coinciding relation to the boundary of said recess.

8. A beauty parlor accessory adapted to serve as a depository for rollers and clips as the same are removed by a hairdresser from the hair of a beauty parlor patron, comprising a tray, a screen located within and spaced from the bottom of said tray and onto which the hairdresser can deposit both rollers and clips indiscriminately, said screen extending across a substantial portion of the expanse of said tray and presenting openings which are large enough to permit clips to pass therethrough but not rollers, said screen at one end region thereof terminating short of the proximate sidewall structure of said tray to define a recess providing access to the lower region of said tray for enabling manual removal of accumulated clips therefrom, and means defining a restraining structure between the main portion of said screen and said recess to cause clips to accumulate under said recess, said means defining a restraining structure comprising an auxiliary receptacle having the same outer contours as said recess and normally supported by said tray within the confines of said recess, said auxiliary receptacle being adapted to serve as a working depository for clips upon removal of the latter from said lower region of said tray.

9. A beauty parlor accessory according to claim 8, further comprising an additional screen extending across and spaced from the bottom of said tray intermediate the bottom of the latter and said first-named screen, the openings in said additional screen being large enough to permit hairs, dandruff and other waste material to pass therethrough but not clips.

10. A beauty parlor accessory according to claim 9, further comprising a removable drawer arranged below said additional screen to facilitate removal of accumulated waste materials.

11. A beauty parlor accessory according to claim 8, said means defining a restraining structure further comprising a barrier disposed in said tray above said screen.

12. A beauty parlor accessory according to claim 11, said barrier being disposed in coinciding relation to the boundary of said recess.
